UNITED STATES PATENT OFFICE.

CHRISTOPHER F. CODA, OF DETROIT, MICHIGAN.

CUSHION SEAT.

1,419,492.

Specification of Letters Patent. Patented June 13, 1922.

Application filed September 3, 1921. Serial No. 498,214.

To all whom it may concern:

Be it known that I, CHRISTOPHER F. CODA, a citizen of the United States of America, residing at Detroit, in the county of Wayne 5 and State of Michigan, have invented certain new and useful Improvements in Cushion Seats, of which the following is a specification, reference being had therein to the accompanying drawings.

10 The invention relates to cushion seats of the type in which the cushion is provided with a skirt which extends downward around the spring frame and is attached to the base thereof.

15 It is the object of the invention to obtain a simple construction which permits of easily attaching the skirt, and to this end the invention consists, first, in the novel construction of the spring frame, and, further, 20 in the means for attaching the skirt thereto, as hereinafter set forth.

In the drawings,

Figure 1 is a bottom plan view of the spring frame, showing the skirt attached to 25 the border wire thereof.

Figures 2 and 3 are cross-sections through the frame showing the manner of attaching the skirt.

Figure 4 is a perspective view of a portion of the frame and skirt.

30 A are the springs, of usual construction, and B, is a base border wire, to which the lower edge of the skirt is attached. Usually the springs A, are attached directly to the 35 border wire B, as well as to cross members extending from side to side of the border frame. This attachment between the border wire and the spring interferes with the attachment of the skirt, particularly where the latter is drawn around beneath the border.

40 I have, therefore, improved the construction by dispensing with the direct connection between the border wire and the adjacent springs, and by supporting the springs 45 solely from cross members. I have also devised a simple construction of cross members which may be readily attached to the border frame without interfering with attachment of the skirt. This construction

50 comprises wires C, having continuous sheet metal strips D of U-shaped cross-section engaging therewith, said strips forming the means of attachment to the springs. More in detail the cross members C with their 55 sheet metal strips B, are arranged in pairs embracing a series of springs A, and engag-

ing diametrically opposite sides of the circular bases A' of said springs. The ends of the wires C project beyond the ends of the strips D which latter terminate inside of 60 the border frame B and the projecting ends of the wire C are then crimped about the border frame to securely attach the same. Transversely of the cross bar C are a pair of wire cross bars E, E', which are clipped 65 to the spring bases of transverse rows of springs, and having their end portions secured to the border wire, as indicated at F. This will form a rigid connection between the border frame and the springs, and at the 70 same time will leave the greater part of the border wire unobstructed for attachment of the skirt thereto.

The skirt G is secured by drawing the lower edge of the same either around the 75 border wire, as indicated at H in Figure 2, or by placing the lower edge adjacent to the border frame, as indicated at I, Figure 3. The skirt is then attached to the frame by a series of U-shaped sheet metal clips J, which 80 are slipped over the border wire and the adjacent skirt and are then crimped to securely clamp the same.

With the construction as described the time required for assembling the cushion 85 with the frame and attachment of the skirt is greatly reduced for the clips J may be rapidly engaged. Also, these clips may be placed all around the skirt and will thus distribute the stress upon the same, consequently the construction is a durable one 90 and one inexpensive to manufacture.

What I claim as my invention is:

1. In a cushion seat, the combination with 95 springs of a base border frame, cross members for attaching said springs to said base border frame each comprising a wire extending adjacent to the spring and a sheet metal strip of U-shape in cross section surrounding said wire and crimped into engagement with each of said springs, said strip having the opposite ends thereof terminating short of the sides of said border frame, the ends of said cross wires being 100 bent into engagement with said base border frame.

2. In a cushion seat, the combination with 110 the springs and a base border frame, of cross bars for attaching said springs to said base border frame each comprising a wire extending adjacent to the lower coil of a series of springs the ends of said wire being

bent into engagement with the border frame, and a sheet metal strip of U-shape in cross section having the opposite ends thereof spaced from the opposite sides of said base 5 border frame, said strip embracing said wire and being clipped to the springs.

3. In a cushion seat, the combination with the springs of a wire base border frame spaced from the springs, a pair of cross bars 10 for connecting series of springs with said base border frame, each comprising a wire having its ends bent about the border wire and sheet metal strips of U-shape in cross section embracing said wires and extending 15 continuously between the opposite sides of the base border frame, said strips having the opposite ends thereof spaced from the sides of said frame and also embracing the spring bases and being clinched into engagement 20 therewith.

4. In a cushion seat, the combination with the springs of a wire base border frame spaced from said springs, cross bars for connecting series of springs with said base 25 border frame, each cross bar consisting of a wire having its ends bent about the wire of the frame and sheet metal members of U- shape in cross section embracing said wires and springs and clinched thereto, said sheet 30 metal members having the opposite ends thereof spaced from the sides of said frame, a skirt and means embracing said border frame and skirt to secure the same to each other.

35 5. In a cushion seat, the combination with a plurality of springs, of a base border frame spaced from said springs, cross members disposed upon opposite sides of said springs and having the ends thereof secured 40 to said frame, and metallic strips surround-

ing said cross members and secured to said springs, said strips terminating short of the sides of said frame.

6. In a cushion seat, the combination with a plurality of springs, of a base border 45 frame spaced from said springs, cross members disposed upon opposite sides of said springs and having the ends thereof secured to said frame, metallic strips surrounding said cross members and secured to said springs, said strips terminating short of the sides of said frame, and cross bars secured to 50 said springs and having the opposite ends thereof secured to said frame, said bars being disposed at right angles to the cross 55 members aforesaid.

7. In a cushion seat, the combination with a plurality of springs, of a base border frame spaced from said springs, cross members disposed upon opposite sides of said 6 springs and having the ends thereof secured to said frame, metallic strips surrounding said cross members and secured to said springs, and cross bars secured to said 65 springs and having the opposite ends thereof secured to said frame.

8. In a cushion seat, the combination with a plurality of springs, of a base border frame spaced from said springs, cross members disposed upon opposite sides of said 70 springs and having the ends thereof secured to said frame, metallic strips surrounding said cross members and secured to said springs, and cross bars secured to said springs and having the opposite ends thereof 75 secured to said frame, said cross bars extending across said strips.

In testimony whereof I affix my signature.

CHRISTOPHER F. CODA.
